FUEL-INJECTION VALVE FOR OIL-ENGINES.

1,341,911.

Specification of Letters Patent.

Patented June 1, 1920.

Application filed December 9, 1918. Serial No. 265,876.

To all whom it may concern:

Be it known that I, KARL OTTO KELLER, a citizen of the Swiss Confederation, residing at Sunderland, in the county of Durham, 5 England, have invented certain new and useful Improvements in Fuel-Injection Valves for Oil-Engines, of which the following is a specification.

This invention relates to fuel-injection 10 valves for oil-engines. The majority of fuel-injection valves heretofore used are provided with a gland packing to prevent gas and oil leakages past the injection needle-valve. The difficulty experienced 15 with the gland packing is that it requires very careful adjustment to prevent it from acting as a brake holding the needle-valve open too long during operation. Further, cases are known wherein the packing has 20 prevented the needle-valve from closing the orifice to the cylinder with the result that the timing of the fuel-injection into the cylinder has been out of control, and the consequences have sometimes proved disastrous. 25 Another objection to the gland packing is that in replacing the needle-valve, particles of the packing material adhere to the tip of the needle-valve when it is pushed through the gland; these particles become jammed 30 between the needle-valve and its seat, or obstruct the narrow passages through which the fuel has to pass.

The needle-valve is usually held against its seat by a spring operating on the valve 35 at the end thereof opposite to the valve-seat, and this spring has had to be strong enough to act as a counterbalance which shall prevent the needle-valve from being blown out by the gas and fuel pressure and shall provide a margin of strength for overcoming 40 gland-friction and inertia forces. In cases where the gas or oil pressures are very high this spring becomes enormous even if the diameter of the needle injection-valve is reduced below satisfactory practical limits. 45

Fuel-injection valves are known wherein the packing has been dispensed with, but the diameter of the needle-valve has of necessity had to be so small, in order that its 50 area should be small enough to enable the spring to put a heavy load on it per square inch of area, that it has not been possible to produce the requisite fit between the needle-valve spindle and its guide to make 55 it reasonably gas- or oil-tight.

This invention is to overcome these objections to known types of fuel-injection valves in a practical way.

One object of the present invention is to construct a fuel-injection valve in which the 60 needle valve is of such diameter that the bore in which the same operates may be readily formed by reaming, internal grinding or lapping.

Another object of the present invention is 65 to render the use of the usual heavy spring for returning the needle valve to its position unnecessary, and utilize in place thereof an operating ram or piston having a pressure equalizing connection with the pressure 70 existing at the entrance of the chamber controlled by the needle valve.

Still another object of the present invention is to provide a light spring at the top end of the ram or piston for keeping the 75 needle valve shut during such time as there is no gas or oil pressure in the system.

A still further object of the present invention is to provide a separate pusher rod between the ram or piston and the needle valve 80 so as to produce an interruption therebetween.

The foregoing and other objects, together with their attendant advantages, will be apparent as the invention becomes better 85 understood by reference to the accompanying specification and drawing forming a part thereof, it being premised that changes may be made in the material employed and details of construction within the scope of 90 the appended claims, without departing from the spirit of the invention.

Referring to the drawing, which illustrates in vertical central section an improved fuel injection valve according to the present invention, there is an upper part or pilot ram 1 and a needle valve proper or lower part 3 operating respectively in the upper and lower cylindrical guides G' and G². It is essential to make the bore in the 100 guide G², in which the needle valve is to operate, of such size as to bring it within the practical possibility of producing a perfectly true bore by the usual commercial workshop processes of reaming, internal grinding or lapping. The grinding and lapping of the needle valve spindle to make it a fluid-tight sliding fit in the guide, then offers no difficulty, and the requisite fit for oil-tightness 105 is easily obtained.

The pilot ram 1, larger in diameter than the needle valve 3, has a fluid-tight sliding fit in the cylindrical guide G' in which it serves as a piston.

5 These guides G' and G² are in vertical alinement, thereby maintaining the pilot ram 1 and the needle valve 3 in alinement and in contact with the opposite ends of a middle part or pusher 2. The upper and 10 lower parts 1 and 3, the former being slightly larger in diameter than the latter, are preferably separate from the middle part or pusher 2, the three parts being so formed that their abutting surfaces at 1^a 2^a 15 and 2^b 3^b are parallel to one another and normal to the vertical axis of the parts 1, 2 and 3, i. e., normal to the line in which all three parts reciprocate.

The upper end of the pilot ram 1, which 20 serves as a piston in the cylindrical guide G², coöperates with a light spring LS kept in place by the screw S and gas tight plug GP. The light spring LS tends normally to maintain the lower tapered end of the needle valve 3 in such position that it closes the fuel opening O leading into the engine cylinder, when there is no pressure in the system.

In order to dispense with the heavy 30 spring which is ordinarily required where a needle valve of large diameter is employed, the upper end of the pilot ram is connected by a pipe BC which maintains constant communication between the top end of the 35 upper cylindrical guide G' and the bottom of the lower cylindrical guide G². This pipe is a pressure-equalizing conduit maintaining a pressure on the pilot ram during the operation of the valve which counter- 40 balances the rod and tends at all times to keep the needle valve shut and overcome friction and inertia forces in the ram and valve. The lower end of the pipe BC communicates with the interior of the cylindrical 45 guide G² by making a junction therewith at J with the fuel-inlet conduits F and F' leading from the source of oil under pressure. Drains D and D² are provided adjacent the abutting surfaces of the upper and 50 lower members with the intermediate pusher rod so as to drain from the cylinder any oil which leaks down the sides of the rod 1 or up the sides of the needle valve 3. The lower end of the cylindrical guide G' and the upper 55 end of the cylindrical guide G² serve respectively as guides for the upper and lower ends of the pusher rod which extend thereinto as shown.

What I claim is:

1. For an oil engine, the combination with 60 a needle valve comprising three parts, the upper part being of greater diameter than the lower part, and all the parts being separate from but abutting against one another, of a cylindrical guide in which the lower 65 part of the needle valve has a fluid-tight sliding fit and in which it serves as a piston controlling the admission of fuel to the engine, and a second cylindrical guide having a closed end and in which the upper part of 70 said needle valve serves as a piston, a source of fuel under pressure, a conduit supplying the fuel to the lower part of the needle valve in said first mentioned cylindrical guide and a pressure equalizing conduit extending 75 therefrom to the upper part of the needle valve in said second mentioned cylindrical guide for equalizing the pressure on opposite sides of the needle valve, substantially as described.

2. For an oil engine, the combination according to claim 1 in a form in which the needle valve is in three parts, the upper and lower parts being separate from but abutting against the middle part, and all three 85 parts so formed that their abutting surfaces are parallel to one another and normal to the line in which all the parts reciprocate, and guides for the upper and lower ends of the middle part, substantially as described. 90

3. In a fuel injection valve, the combination with a smaller guide constituting a cylinder, said cylinder having a fuel inlet port situated at one end thereof and having a fuel passage leading to said port by way 95 of the end of the cylinder adjacent thereto, a larger cylindrical guide, a normally closed needle valve controlling said port and arranged to open upwardly in a direction reverse to that of the flow of the fuel and 100 having a two-diameter stem whereof the part of smaller diameter constitutes a piston in the smaller guide and the part of larger diameter constitutes a ram in said larger guide, of means for subjecting the end of 105 said ram remote from said port to the downward fuel pressure that acts upwardly on the end of said piston adjacent to said port, for the purpose specified.

In testimony whereof I have signed my 110 name to this specification in the presence of two subscribing witnesses.

KARL OTTO KELLER.
